(57) CLAIM

The ornamental design for a wardrobe, as shown and described.

DESCRIPTION

FIG. 1 is a perspective view of a wardrobe showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged perspective view of an upper right-hand portion of the wardrobe.

The broken lines in the drawings illustrate portions of the wardrobe that form no part of the claimed design.

1 Claim, 6 Drawing Sheets
